UNITED STATES PATENT OFFICE.

GUSTAVE M. NELL, OF DENVER, COLORADO, ASSIGNOR TO THE DENVER ROCK DRILL MANUFACTURING COMPANY, OF DENVER, COLORADO, A CORPORATION OF DELAWARE.

MEANS FOR OPENING THE BORES OF ROCK-DRILLING STEELS.

1,388,437.

Specification of Letters Patent. Patented Aug. 23, 1921.

Application filed June 14, 1919. Serial No. 304,296.

To all whom it may concern:

Be it known that I, GUSTAVE M. NELL, a citizen of the United States, residing at Denver, in the county of Denver and State 5 of Colorado, have invented certain new and useful Improvements in Means for Opening the Bores of Rock-Drilling Steels, of which the following is a specification.

The present invention relates to means for 10 opening the bores of rock drilling steels. As is well known to those skilled in the art, in manufacturing, sharpening, and repairing drill steels of that type having longitudinal bores therethrough, these bores are apt to become partly closed or misshapen, and it is 15 desirable that the same in the completed steel be fully open.

The primary object of the present invention is to provide means of a novel and practical character for effectively mounting bore 20 opening apparatus on a drill sharpener, so that the usual steel clamping mechanism may be utilized for holding the drill steels while the bores are being opened, the bore opening 25 apparatus being in the form of an attachment that can be placed upon the sharpening apparatus without materially altering or modifying its structure.

A further object is to so arrange the 30 mounting that it may also constitute a support for a pin extractor, thereby providing a common support or attachment for both mechanisms.

An embodiment of the invention that is 35 at present considered the preferable one, is illustrated in the accompanying drawings, wherein:—

Figure 1 illustrates in outline a drill sharpener with the opening apparatus and 40 its mounting in place thereon.

Fig. 2 is a detail perspective view of the mounting,

Fig. 3 is a detail horizontal sectional view of a portion of the mounting and the adjacent portion of the drill sharpener base to which is attached,

Fig. 4 is a plan view of the mounting with the pin extractor in place,

Fig. 5 is a detail perspective view of the extractor supporting yoke,

Fig. 6 is a longitudinal sectional view through the bore opening apparatus, and

Fig. 7 is a detail sectional view through the pin extractor.

Similar reference numerals designate corresponding parts in all the figures of the drawings.

In the embodiment illustrated, the drill sharpener is shown as comprising a base formed of sections 8—9 held together by 55 bolts 10. Coöoperating relatively movable jaw members 11 and 12 are mounted on the base and are provided with the usual supplemental jaws 13 and 14. These jaw members, as are well understood by those skilled 60 in the art, are operated by fluid actuating mechanism, in the present instance the section 9 being a cylinder and containing a piston, not shown, that is connected by a piston rod 15 with the upper movable jaw 65 member 11. This structure is well known 70 and it is believed needs no further exposition.

In the present embodiment, a bracket arm 16 is provided, the outer end of which has a 75 substantially horizontal flat surface 17, the intermediate portion 18 having angularly disposed ribs, and the inner end having a curved portion 19 that corresponds to the upper peripheral surface of the drill 80 sharpener base to which it is secured by suitable bolts, as 20 passing therethrough and threaded into the said base. A brace 21 supports the outer end of the arm 16, having a horizontal portion 22 located beneath 85 the portion 17, and having at its lower and inner end an ear 23 provided with an opening 24 through which is passed one of the bolts 10 that holds the sections 8 and 9 of the base together.

Secured to the outer end of the bracket, thus formed, is bore opening mechanism described generally by the reference numeral 25. This bore opening mechanism includes a cylinder member 26 having a base 27 that 90 is secured upon the horizontal end portions 17 and 22 of the bracket by bolts 28 that not only serve to hold the base to the bracket, but also fasten the parts 17 and 22 together by passing through both.

The cylinder member is provided with heads 29, and operating therein, is a tubular piston having a head 30 and oppositely extending reduced portions 31 that slidably pass through the heads 29. The said tubular piston provides a piston chamber 32 closed by a front head 33 and by a rear head 34, the latter held in place by a tubular

plug 35. The front head 33 contains a tappet 36, the rear end of which projects into the chamber 32, the front end projecting beyond the head 33, and having a socket 37 to receive the rear end of a tapered punch pin 38. This pin may be held in place by a transverse key 39, and the arrangement is such that the pin will be alined with the bore of a drill steel clamped by the jaws 13 and 14. A reciprocatory hammer piston 41 operates in the chamber 32 and strikes against the rear end of the tappet 36, said piston having a rearward extension or neck 42 that is slidable in the head 34 and projects into the chamber 43 of the plug 35. The actuating fluid to the apparatus is controlled by a suitable valve having a handle, shown at 44.

It is however, believed to be unnecessary to go into detail regarding the distribution of the motive fluid, beyond the statement that when the throttle valve is turned in one direction motive fluid will be admitted to reciprocate the hammer piston 41, resulting in rapidly repeated blows against the tappet, and these blows will, of course, be transmitted to the punch pin 38. At the same time motive fluid may be admitted to the cylinder member 26 on either side of the piston 30 therein, so that the hammer mechanism may be advanced toward or withdrawn from the drill steel during the operation of the hammer piston. It will thus be clear that when a drill steel has been properly shaped, sharpened or otherwise operated upon, and while its end is still heated to permit working of the metal, if it is clamped between the jaws 13 and 14, the punch pin may be advanced so that the free end thereof will enter the bore, and at the same time the hammer piston being in operation, will drive the same into the bore and properly open it. When so opened the punch pin can be withdrawn.

45 The supporting and securing means may also afford convenient means for holding in place a pin extracting apparatus. To this end, a yoke 45 is employed having its ends secured to the bracket and to the base of the drill sharpener by the bolts 20, as clearly illustrated in Fig. 4. This yoke, in turn, has bolted to it, a base 46 having at one end a socket 47 for receiving the end of a drill steel, the said socket being provided with 50 an aperture 48 in its rear end, which aperture is of less diameter than the diameter of the drill steel. A guide bar 49 extends rearwardly from the socket, and has slidably mounted thereon a carriage 50 provided 55 with a clamping cam 51. This carriage has a link connection 52 with a lever 53 fulcrumed, as shown at 54 on the rear end of the guide bar.

In using the extractor, the end of the 60 drill steel with the pin projecting there-

from is placed in the socket 47 with the projecting portion of said pin extending through the aperture 48. This projecting end is clutched by operating the cam 51 and the carriage is then moved rearwardly by 65 means of the lever 53, whereupon the pin will be withdrawn.

It will be obvious that the mounting above described is simple and has been found entirely practicable and successful for attaching drill steel bore opening means to a drill sharpener in position to coöperate with the jaws of the sharpener. It will be noted moreover that the mounting can be easily placed in position and does not require material modification of the drill sharpener structure. It also provides effective means for securing in place a pin extractor when so desired.

From the foregoing, it is thought that the 85 construction, operation and many advantages of the herein described invention will be apparent to those skilled in the art, without further description, and it will be understood that various changes in the size, 90 shape, proportion and minor details of construction may be resorted to without departing from the spirit or sacrificing any of the advantages of the invention.

Having thus fully described my invention, 95 what I claim as new, and desire to secure by Letters Patent, is:—

1. In apparatus of the character set forth, the combination with a drill sharpening machine having relatively movable drill steel 100 clamping jaws, of a bracket arm secured at one point to the machine, a brace for the arm connected to another portion of the machine, and bore opening mechanism mounted on the bracket in position to enter 105 the bore of a drill steel held by the jaws.

2. In apparatus of the character set forth, the combination with a drill sharpening machine including a sectional base, means holding the base sections together and relatively 110 movable drill steel clamping jaws mounted on the base, of a bracket arm secured to the base, a brace for the arm having its end secured to the base by the means which secures the base sections together, and bore 115 opening mechanism mounted on the bracket arm in position to enter the bore of a drill steel held by the jaws.

3. In apparatus of the character set forth, the combination with a drill sharpening machine having relatively movable drill steel clamping jaws, of a bracket arm secured at one point to the machine, a brace for the arm connected to another portion of the machine, bore opening mechanism mounted 120 on the bracket in position to enter the bore of a drill steel held by the jaws, and common 125 means for securing the bore opening mechanism to the arm and also securing the arm and brace together.

4. In apparatus of the character set forth, the combination with a drill sharpening machine including a sectional base, bolts holding the base sections together and relatively 5 movable drill steel clamping jaws mounted on the base, of a bracket arm secured to the base below the jaws, a brace for the arm having its inner end secured to the base by one of the bolts which fastens the base sections 10 together and having its outer end beneath the outer end of the arm, bore opening mechanism mounted on the bracket arm in position to enter the bore of a drill steel held by the jaws of the drill sharpening machine, 15 and bolts passing through the brace and arm and engaging the bore opening mechanism to secure the same in place.
5. An attachment of the character set forth, comprising a bracket arm having 20 means for securing it to a drill sharpener, bore opening means mounted on the arm and adapted when said arm is in place on a drill sharpener, to enter the bore of a drill steel held by the jaws of said drill sharpener, and 25 a brace for the arm secured thereto and hav-
- ing means for attachment to the drill sharpener.
6. An attachment of the character set forth, comprising a bracket, drill steel bore opening apparatus mounted thereon, and 30 means for securing the bracket at spaced points to the base of a drill sharpening machine, to position the opening apparatus, to enter the bore of a drill steel secured by the jaws of said sharpener. 35
7. An attachment of the character set forth, comprising a pin extracting mechanism, a mounting for the same having devices for fastening it to the base of a drill sharpener, and bore opening mechanism including a support engaged by and adapted to be fastened to the base of said drill sharpener by the mounting of the pin extracting mechanism. 40

In testimony whereof, I affix my signature 45
in the presence of two witnesses.
